UNITED STATES PATENT OFFICE.

WILLIAM G. PRICE, OF NEW CASTLE, PENNSYLVANIA.

DAMPING DEVICE FOR TRUCK-BOLSTERS.

1,073,627.

Specification of Letters Patent. Patented Sept. 23, 1913.

Application filed April 28, 1913. Serial No. 764,160.

To all whom it may concern:

Be it known that I, WILLIAM G. PRICE, a citizen of the United States, and resident of New Castle, in the county of Lawrence and State of Pennsylvania, have invented a new and useful Improvement in Damping Devices for Truck-Bolsters; and I do hereby declare the following to be a full, clear, and exact description thereof.

10 My invention relates to railway car-trucks, and more especially to a device for damping the swing and rolling of the bolster.

It is common practice in railway car-trucks to mount the bolster upon swinging supports so that the bolster is free to swing longitudinally with respect to itself, and also move vertically by an end-wise movement. By allowing for this movement of 20 the bolster the bolster is permitted to conform to the change of direction of the car body when rounding curves, on rough tracks and the like, and as a result better riding of the car is obtained. Unless this longitudinal and rocking movement of the bolster, however, is put under restraint the movement becomes cumulative and the swinging and rocking of the bolster becomes so great as to occasion the discomforture of the passengers within the car.

The object of my present invention is to provide a simple and efficient device by means of which this longitudinal and rocking movement of the bolster may be damped, 35 and to these ends the invention comprises the novel features hereinafter set forth and claimed.

In the accompanying drawing Figure 1 is a plan view of a portion of a truck and 40 bolster showing my invention applied thereto; Fig. 2 is a section on the line 2—2 Fig. 1; Fig. 3 is a section on the line 3—3 Fig. 1; and Fig. 4 is a detail.

In the drawing the numeral 2 designates 45 the side frame of a suitable truck to which the transoms 3 are connected. The bolster 4 is supported by the swinging supports 5 which are pivotally connected to the transom and the lower ends thereof engaging 50 the leaf springs all in the ordinary manner. In this way the bolster is permitted to swing longitudinally and as the swinging supports are normally slightly inclined it is apparent that any longitudinal movement 55 of the bolster will be attended with a slight

vertical movement or rocking end-wise of the bolster.

Secured to the side frame 2 is the plate 6 which is held in place by the bolts 7. This plate has the inclined face 8. A damper-plate 9 is provided which may be bell-crank in form, having the arm 10 which engages the inclined face 8 of the plate 6 and forms a fulcrum therewith. The damper-plate 9 is formed channel-shaped with the upper 65 flange 11 and the lower flange 12. The flange 11 rests upon the lower guide plate 13 which is supported by the transom 3 and an upper guide plate 14 is provided, said guide plates being secured to the transom by the 70 bolts 15. The upper flange 11 of the damper-plate has a slight amount of vertical play between the two guide plates 13 and 14 to permit of the slight vertical movement of the damper plate. The damper plate is 75 provided with the downwardly extending portion 16 which is adapted to engage the side of the bolster 4.

A bolt 17 passes through the arm 10 of the damper plate and through the plate 6 80 and through the side frame 2. A spring 18 is carried by the bolt 17, said spring being interposed between the side frame and the dished washer 19 on the bolt 17. The ordinary nut 20 and jam nut 21 are provided 85 by means of which the tension of the spring 18 may be regulated. The action of the spring 18 is to draw the damper-plate outwardly at the side frame and hold the plate against the inclined face 8 of the plate 6. 90 This also tends to force the inner end of the damper-plate against the bolster due to the fulcrum action. A spring 22 is provided which bears against the outer end of the projecting portion 16 so as to force said portion 95 against the bolster and said spring is interposed between said plate and the transom. This spring passes through the bolster hanger bracket 23 and this forms a seat for the outer end of said spring to hold it in 100 proper position.

When the bolster swings longitudinally of itself due to the action of the truck in rounding curves or for other reasons, the swing is damped by the damper-plates and 105 the frictional contact of the damper-plate 11 is controlled by the action of the springs 18 and 22, and it is of course apparent that the tension of the spring 18 can be varied to suit conditions. The action of the spring 110

18 tends to hold the arm 10 of the damper-plate in contact with the inclined face 8 of the plate 6 and this action together with that of the spring 22 acts to hold the downwardly projecting portion 16 of the damper-plate in full contact with the bolster and any wear that takes place is taken up in this way. Furthermore, the action of these springs 18 and 22 is to hold the bolster in contact with the damper-plate at the opposite side of the bolster, and when the brakes are applied the bolster will have a tendency to move away from the damper-plate, and in that case the damper-plate 11 yields sufficiently to take care of this movement. Furthermore, the sidewise or lateral movement of the bolster is checked as well as the rocking and end swing of the bolster.

What I claim is:

20. 1. In a car-truck, the combination with the frame, of a swing-bolster between the transoms of the same, a spring actuated damper-plate supported from the frame having a diagonal movement with reference to the bolster, and a portion on said damper plate engaging the side of the bolster.
25. 2. In a car-truck, the combination with the frame, of a swing-bolster between the transoms of the same, a movable damper-plate supported from the frame, means tending to draw said damper-plate outwardly, and means carried by the frame engaged by said damper-plate to move the same laterally.
30. 3. In a car-truck, the combination with the frame, of a swing-bolster between the transoms of the same, a spring actuated damper-plate supported from the frame and engaging the bolster, means tending to move said damper-plate longitudinally, an arm on said damper-plate, and an abutment on the frame with which said arm engages.
35. 4. In a car-truck, the combination with the frame, of a swing-bolster between the transoms of the same, a spring actuated damper-plate supported from the frame and engaging the bolster, an arm on said plate, a bolt engaging said arm and connecting same to the frame, a spring on said bolt to draw said plate outwardly, and an abutment on the frame with which said arm engages, and a spring bearing against the damper-plate.

5. In a car-truck, the combination with the frame, of a swing-bolster between the transoms of the same, a movable damper-plate supported from the frame and engaging the bolster, an arm on said plate, a bolt engaging said arm and connecting it to the frame, a spring on said bolt, an inclined abutment on the frame with which said arm engages, and a spring bearing against said plate.

6. In a car-truck, the combination with the frame, of a swing-bolster between the transoms of the same, a movable damper-plate, an arm on said plate, a bolt engaging said arm and connecting same to the frame, a spring on said bolt interposed between said frame and a stop on said bolt, an inclined abutment on the frame engaged by said arm, and a spring engaging said plate interposed between the same and the frame.

7. In a car-truck, the combination with the frame, of a swing-bolster between transoms of the same, a bell-crank damper-plate, one arm of which engages the bolster, an abutment on the frame with which said damper engages to form a fulcrum and a spring supported by the frame acting on one arm of said damper to draw the other arm toward the bolster.

8. In a car-truck, the combination with the frame, of a swing-bolster between the transoms of the same, a movable bell-crank damper-plate fulcrumed on the same, and a spring supported by the frame acting on one arm of said bell-crank to draw the other arm toward the bolster.

9. In a car-truck, the combination with the frame, of a swing-bolster between the transoms of the same, a movable bell-crank damper-plate fulcrumed on said frame, a spring supported by the frame acting to draw the outer end of one arm of said bell-crank outwardly, and the inner end of the other arm toward the bolster, and a spring engaging the outer end of said second arm and supported by the frame.

In testimony whereof, I the said WILLIAM G. PRICE have hereunto set my hand.

WILLIAM G. PRICE.
